ABSTRACT: Novel compounds of the formula:

wherein:

(1) R_1 is a straight or branched higher alkyl group of C_6 to C_{20} , and preferably C_{10} to C_{22} ;

NOVEL COMPOUNDS WITH DETERGENCY AND
FABRIC-SOFTENING ABILITY AND METHOD OF
MAKING THE SAME

The present invention relates to novel compounds uniquely containing foaming and detergency properties in addition to fabric-softening ability, methods of preparing the same, and novel intermediate compounds useful in their preparation. More particularly, the present invention relates to such novel compounds of the hydroxy ether (including thioether) sulfonate type.

While in recent years various outstanding detergent materials and various outstanding softening agents have been developed, it has still been necessary to provide separate materials for performing these two functions. Thus, until the present invention no successful detergent material possessing softening ability has been discovered.

The most successful detergents developed in recent years are the linear alkyl benzene sulfonates. While such materials possess excellent foaming and detergency characteristics such materials possess little or no softening ability.

The most effective softeners that have been developed in recent years are the quaternary ammonium fabric-softening agents. While these cationic agents are extremely effective in the softening of textile fabrics, it is noted that, because of their cationic nature, such fabric-softening additives cannot be employed in conjunction with conventional anionic detergents, e.g. sulfonates, and therefore, must be added to the wash water during the rinse cycle operation. This is due to the fact that the cationic quaternary ammonium fabric softeners and anionic detergents complex and precipitate thus adversely effecting the operability of each of the materials.

Accordingly, in accordance with previous materials and methods, the use of separate detergents and fabric softeners has been even more complicated by the incompatibility of the best detergents and fabric softeners previously available.

Therefore, it has been the long desire of the detergent industry to provide a single compound possessing the foaming detergency characteristics of conventional detergents, yet uniquely possessing fabric-softening ability. Such a single compound uniquely possessing both detergency and fabric-softening ability would of course eliminate the disadvantages of employing two separate materials, and, in addition, would completely eliminate the disadvantages associated with the incompatibility of conventional anionic detergents and cationic fabric softeners.

In accordance with the present invention, it has now been discovered that certain hydroxy ether sulfonates possess detergency characteristics substantially equivalent to or better than that of conventional anionic detergents now employed in detergent compositions and, in addition, possess fabric-softening ability substantially equivalent to quaternary ammonium cationic fabric softeners now conventionally employed in the rinse cycle of a washing operation.

It is therefore a principle object of the present invention to provide a detergent compound possessing fabric-softening ability.

It is a further object of the present invention to provide such a novel detergent compound possessing fabric-softening ability which novel compound eliminates the previous deficiencies associated with the employment of separate incompatible detergents and fabric softeners.

A yet further object of the present invention is to provide certain novel hydroxy ether sulfonates which possess detergency and foaming characteristics substantially equivalent to or superior to conventional anionic detergents and fabric-softening ability substantially equivalent to conventional cationic quaternary ammonium softeners.

Still a further object of the present invention is to provide novel methods of producing certain hydroxy ether sulfonates possessing both detergency and fabric-softening ability, such processes including the reaction of an unsaturated alcohol with a long-chain epoxide with subsequent sulfonation of the reaction product.

Yet a further object of the present invention is to provide novel unsaturated hydroxy ethers useful as intermediates in the production of the hydroxy ether sulfonates of the present invention.

5 Still another further object of the present invention is the provision of novel hydroxy ether sulfonates which are compatible with builder salts and particularly tetrapotassium pyrophosphate in aqueous systems obviating the need for hydrotropic agents.

10 Still further objects and advantages of the novel compounds and process of the present invention will become more apparent from the following more detailed description thereof.

The novel compounds of the present invention which uniquely possess outstanding foaming and detergency characteristics in addition to fabric-softening ability correspond to the general formula:

wherein:

1. R_1 is a straight or branched higher alkyl group of C_6 to C_{30} , and preferably C_{10} to C_{22} ;

30 2. R_2 is a straight or branched alkylene of C_3 to C_{12} , and preferably C_4 to C_6 ;

3. R_3 to R_7 are, independently, hydrogen or straight or branched alkyl of C_1 to C_{10} , and preferably hydrogen or lower alkyl of C_1 to C_4 ;

4. Z is oxygen ($-\text{O}-$) or sulfur ($-\text{S}-$);

5. x and y have the values 0 or 1 and $x+y=1$; and

6. M is a cation such as hydrogen, alkali metal, ammonium, substituted ammonium or amine and preferably a water-solubilizing, salt-forming group.

40 While the sodium salts of the hydroxy ether sulfonates of the present invention are preferred, it is of course possible to advantageously employ other alkali metals such as potassium or lithium. Additionally, ammonium and amine salts, e.g., tri-alkanolamine salts such as triethanolamine can be advantageously employed with exceptional results.

45 The novel hydroxy ether sulfonates of the present invention may be prepared by reacting an epoxy alkane with an unsaturated aliphatic alcohol with subsequent sulfonation of the reaction product. The epoxy alkane reactants that are useful

50 in the preparation of the hydroxy ether sulfonates of the present invention can be any epoxy alkane having a terminal group i.e., an epoxy alkane having the structure:

wherein R_1 is as defined above. As noted above, R_1 comprises a straight or branched-chain alkyl radical of from about six to about 30 carbon atoms. Illustrative examples of some suitable alkyl radicals include:

n-hexyl

iso-hexyl

n-heptyl

iso-heptyl

n-octyl

iso-octyl

n-nonyl

iso-nonyl

n-decyl

n-dodecyl

tert-dodecyl

2-propylheptyl

5-ethylnonyl

2-butyloctyl

n-undecyl
n-tridecyl
n-tetradecyl
n-pentadecyl
tert-octadecyl
2,6,8-trimethylnonyl
7-ethyl-2-methyl-4-undecyl
n-hexadecyl
n-octadecyl
eicosyl
docosyl
tricosyl
pentacosyl
triacontyl etc.

The alkyl radicals may also include unsaturated alkyl radicals such as hexenyl, oleyl, dodecenyl, hexadecenyl, and the like.

Illustrative examples of some epoxy alkanes which can be employed as reactants in the process of the present invention to produce the novel hydroxy ether sulfonates of the present invention include:

1,2 epoxyhexane
1,2 epoxoctane
1,2 epoxydecane
1,2 epoxyundecane
1,2 epoxydodecane
1,2 epoxytridecane
1,2 epoxytetradecane
1,2 epoxypentadecane
1,2 epoxyhexadecane
1,2 epoxyoctadecane
7-ethyl-2-methyl-1,2-epoxyundecane
2,6,8-trimethyl-1,2-epoxynonane
1,1,2-trimethyl-1,2-epoxy decane
1,1-dimethyl-2-ethyl-epoxy decane -epoxy decane
1-methyl-1,2-diethyl-1,2-epoxy tetradecane
1,1-dimethyl epoxy undecane
1,1-diethyl epoxy decane
1,1-diisopropyl epoxy octane etc.

Exemplary hydroxy ether sulfonates in accordance with the present invention include:

A. Oxa derivatives

1. wherein $y=1$ and $x=0$
6-hydroxy-4-oxahexadecyl sodium sulfonate
6-hydroxy-4-oxaheptadecyl sodium sulfonate
6-hydroxy-4-oxaoctadecyl sodium sulfonate
6-hydroxy-4-oxanonadecyl sodium sulfonate
6-hydroxy-4-oxaeicosyl sodium sulfonate
6-hydroxy-4-oxauncosyl sodium sulfonate
6-hydroxy-4-oxadocosyl sodium sulfonate
6-hydroxy-8-methyl-12-ethyl-4-oxapentadecyl sodium sulfonate
6-hydroxy-7,7-dimethyl-4-oxahexadecyl sodium sulfate
6-hydroxy-4-oxatetracosyl sodium sulfonate
6-hydroxy-4-oxahexadecyl potassium sulfonate
6-hydroxy-4-oxaheptadecyl potassium sulfonate
6-hydroxy-4-oxaoctadecyl potassium sulfonate
6-hydroxy-4-oxanonadecyl potassium sulfonate
6-hydroxy-4-oxaeicosyl potassium sulfonate
6-hydroxy-4-oxauncosyl potassium sulfonate
6-hydroxy-4-oxadocosyl potassium sulfonate
6-hydroxy-8 methyl12-ethyl-4-oxapentadecyl potassium sulfonate
6-hydroxy-7,7-dimethyl-4-oxahexadecyl potassium sulfonate
6-hydroxy-4-oxatetracosyl potassium sulfonate
6-hydroxy-4-oxahexadecyl lithium sulfonate
6-hydroxy-4-oxaheptadecyl lithium sulfonate
6-hydroxy-4-oxaoctadecyl lithium sulfonate
6-hydroxy-4-oxanonadecyl lithium sulfonate
6-hydroxy-4-oxadocosyl lithium sulfonate
6-hydroxy-4-oxahexadecyl ammonium sulfonate
6-hydroxy-4-oxaeicosyl ammonium sulfonate
6-hydroxy-4-oxauncosyl ammonium sulfonate
6-hydroxy-4-oxadocosyl ammonium sulfonate

6-hydroxy-8 methyl-12-ethyl-4-oxapentadecyl ammonium sulfonate
triethanol amine salt of 6-hydroxy-4-oxahexadecyl sulfonic acid
5 triethanol amine salt of 6-hydroxy-4-oxaheptadecyl sulfonic acid
triethanol amine salt of 6-hydroxy-4-oxaeicosyl sulfonic acid
triethanol amine salt of 6-hydroxy-7,7-dimethyl-4-oxahexadecyl sulfonic acid
8-hydroxy-6-oxahexadecyl sodium sulfonate
8-hydroxy-6-oxaheptadecyl sodium sulfonate
8-hydroxy-6-oxaoctadecyl sodium sulfonate
8-hydroxy-6-oxanonadecyl sodium sulfonate
8-hydroxy-6-oxaeicosyl sodium sulfonate
8-hydroxy-6-oxauncosyl sodium sulfonate
8-hydroxy-6-oxadocosyl sodium sulfonate
8-hydroxy-8 methyl-12-ethyl-6-oxapentadecyl sodium sulfonate
8-hydroxy-11,11, dimethyl-6-oxahexadecyl sodium sulfonate
8-hydroxy-6-oxatetracosyl sodium sulfonate
8-hydroxy-6-oxahexadecyl potassium sulfonate
8-hydroxy-6-oxaheptadecyl potassium sulfonate
8-hydroxy-6-oxaoctadecyl potassium sulfonate
8-hydroxy-6-oxanonadecyl potassium sulfonate
8-hydroxy-6-oxaeicosyl potassium sulfonate
8-hydroxy-6-oxauncosyl potassium sulfonate
8-hydroxy-6-oxadocosyl potassium sulfonate
8-hydroxy-8 methyl-12-ethyl-6-oxapentadecyl potassium sulfonate
8-hydroxy-11,11-dimethyl-6-oxahexadecyl potassium sulfonate
8-hydroxy-6-oxatetracosyl potassium sulfonate
8-hydroxy-6-oxahexadecyl lithium sulfonate
8-hydroxy-6-oxaoctadecyl lithium sulfonate
8-hydroxy-6-oxanonadecyl lithium sulfonate
8-hydroxy-6-oxadocosyl lithium sulfonate
8-hydroxy-6-oxahexadecyl ammonium sulfonate
8-hydroxy-6-oxaheptadecyl ammonium sulfonate
8-hydroxy-6-oxaeicosyl ammonium sulfonate
8-hydroxy-6-oxadocosyl ammonium sulfonate
8-hydroxy-8 methyl-12-ethyl-6-oxapentadecyl ammonium sulfonate
triethanol amine salt of 8-hydroxy-6-oxahexadecyl sulfonic acid
triethanol amine salt of 8-hydroxy-6-oxaheptadecyl sulfonic acid
50 triethanol amine salt of 8-hydroxy-6-oxaeicosyl sulfonic acid
triethanol amine salt of 8-hydroxy-9,9-dimethyl-6-oxahexadecyl sulfonic acid
7-hydroxy-5-oxahexadecyl sodium sulfonate
55 7-hydroxy-5-oxaoctadecyl sodium sulfonate
7-hydroxy-5-oxaeicosyl sodium sulfonate
7-hydroxy-5-oxadocosyl sodium sulfonate
7-hydroxy-9,9-dimethyl-5-oxahexadecyl sodium sulfonate
7-hydroxy-5-oxahexadecyl potassium sulfonate
60 7-hydroxy-5-oxaoctadecyl potassium sulfonate
7-hydroxy-5-oxaeicosyl potassium sulfonate
7-hydroxy-5-oxadocosyl potassium sulfonate
7-hydroxy-9,9-dimethyl-5-oxahexadecyl potassium sulfonate
7-hydroxy-5-oxahexadecyl lithium sulfonate
65 7-hydroxy-5-oxanondecyl lithium sulfonate
7-hydroxy-5-oxahexadecyl ammonium sulfonate
7-hydroxy-5-oxaeicosyl ammonium sulfonate
7-hydroxy-8 methyl-12-ethyl-5-oxapentadecyl ammonium sulfonate
70 triethanol amine salt of 7-hydroxy-5-oxaheptadecyl sulfonic acid
triethanol amine salt of 7-hydroxy-7,7-dimethyl-5-oxahexadecyl sulfonic acid
75 10-hydroxy-8-oxahexadecyl sodium sulfonate

10-hydroxy-8-oxaoctadecyl sodium sulfonate
 10-hydroxy-8-oxaeicosyl sodium sulfonate
 10-hydroxy-8-oxadocosyl sodium sulfonate
 10-hydroxyl-7,7-dimethyl-8-oxahexadecyl sodium sulfonate
 10-hydroxy-8-oxahexadecyl potassium sulfonate
 10-hydroxy-8-oxaoctadecyl potassium sulfonate
 10-hydroxy-8-oxaeicosyl potassium sulfonate
 10-hydroxy-8-oxadocosyl potassium sulfonate
 10-hydroxy-7,7-dimethyl-8-oxahexadecyl potassium sulfonate
 10-hydroxy-8-oxahexadecyl lithium sulfonate
 10-hydroxy-8-oxanoadecyl lithium sulfonate
 10-hydroxy-8-oxahexadecyl ammonium sulfonate
 10-hydroxy-8-oxaeicosyl ammonium sulfonate
 10-hydroxy-14 methyl-12-ethyl-8-oxapentadecyl ammonium sulfonate
 triethanol amine salt of 10-hydroxy-8-oxahetadecyl sulfonic acid
 triethanol amine salt of 10-hydroxy-7,7-dimethyl-8-oxahexadecyl sulfonic acid
 11-hydroxy-9-oxahexadecyl sodium sulfonate
 11-hydroxy-9-oxaeicosyl sodium sulfonate
 11-hydroxy-7,7-dimethyl-9-oxahexadecyl sodium sulfonate
 11-hydroxy-9-oxaoctadecyl potassium sulfonate
 11-hydroxy-9-oxadocosyl potassium sulfonate
 11-hydroxy-9-oxahexadecyl lithium sulfonate
 11-hydroxy-9-oxahexadecyl ammonium sulfonate
 11-hydroxy-8 methyl-12-ethyl-9-oxapentadecyl ammonium sulfonate
 triethanol amine salt of 11-hydroxy-7,7-dimethyl-9-oxahexadecyl sulfonic acid
 12-hydroxy-10-oxahexadecyl sodium sulfonate
 12-hydroxy-10-oxaeicosyl sodium sulfonate
 12-hydroxy-7,7-dimethyl-10-oxahexadecyl sodium sulfonate
 12-hydroxy-10-oxaoctadecyl potassium sulfonate
 12-hydroxy-10-oxadocosyl potassium sulfonate
 12-hydroxy-10-oxahexadecyl lithium sulfonate
 12-hydroxy-10-oxahexadecyl ammonium sulfonate
 12-hydroxy-8 methyl-14-ethyl-10-oxapentadecyl ammonium sulfonate
 triethanol amine salt of 12-hydroxy-7,7-dimethyl-10-oxahexadecyl sulfonic acid
 15-hydroxy-13-oxahexadecyl sodium sulfonate
 15-hydroxy-13-oxaeicosyl sodium sulfonate
 15-hydroxy-7,7-dimethyl-13-oxahexadecyl sodium sulfonate
 15-hydroxy-13-oxaoctadecyl potassium sulfonate
 15-hydroxy-13-oxadocosyl potassium sulfonate
 15-hydroxy-13-oxahexadecyl lithium sulfonate
 15-hydroxy-13-oxahexadecyl ammonium sulfonate
 15-hydroxy-8 methyl-12-ethyl-13-oxapentadecyl ammonium sulfonate
 triethanol amine salt of 15-hydroxy-7,7-dimethyl-13-oxahexadecyl sulfonic acid
 2. wherein $y=0$ and $x=1$
 5-hydroxymethyl-4-oxahexadecyl sodium sulfonate
 5-hydroxymethyl-4-oxaeicosyl sodium sulfonate
 5-hydroxymethyl-7,7-dimethyl-4-oxahexadecyl sodium sulfonate
 5-hydroxymethyl-4-oxaoctadecyl potassium sulfonate
 5-hydroxymethyl-4-oxadocosyl potassium sulfonate
 5-hydroxymethyl-4-oxahexadecyl lithium sulfonate
 5-hydroxymethyl-4-oxahexadecyl ammonium sulfonate
 5-hydroxymethyl-8 methyl-12-ethyl-4-oxapentadecyl ammonium sulfonate
 triethanol amine salt of 5-hydroxymethyl-7,7-dimethyl-4-oxahexadecyl sulfonic acid
 6-hydroxymethyl-5-oxahexadecyl sodium sulfonate
 6-hydroxymethyl-7,7-dimethyl-5-oxahexadecyl sodium sulfonate
 6-hydroxymethyl-5-oxaoctadecyl potassium sulfonate
 6-hydroxymethyl-5-oxadocosyl potassium sulfonate
 6-hydroxymethyl-5-oxahexadecyl lithium sulfonate

6-hydroxymethyl-5-oxahexadecyl ammonium sulfonate
 6-hydroxymethyl-8 methyl-12-ethyl-5-oxapentadecyl ammonium sulfonate
 triethanol amine salt of 6-hydroxy-7,7-dimethyl-5-oxahexadecyl sulfonic acid
 7-hydroxymethyl-6-oxahexadecyl sodium sulfonate
 7-hydroxymethyl-6-oxaeicosyl sodium sulfonate
 7-hydroxymethyl-9,9-dimethyl-6-oxahexadecyl sodium sulfonate
 7-hydroxymethyl-6-oxaoctadecyl potassium sulfonate
 7-hydroxymethyl-6-oxadocosyl potassium sulfonate
 7-hydroxymethyl-6-oxahexadecyl lithium sulfonate
 7-hydroxymethyl-6-oxahexadecyl ammonium sulfonate
 7-hydroxymethyl-8 methyl-12-ethyl-6-oxapentadecyl ammonium sulfonate
 triethanol amine salt of 7-hydroxymethyl-9,9-dimethyl-6-oxahexadecyl sulfonic acid
 8-hydroxymethyl-7-oxahexadecyl sodium sulfonate
 8-hydroxymethyl-7-oxaeicosyl sodium sulfonate
 8-hydroxymethyl-5,5-dimethyl-7-oxahexadecyl sodium sulfonate
 8-hydroxymethyl-7-oxaoctadecyl potassium sulfonate
 8-hydroxymethyl-7-oxadocosyl potassium sulfonate
 8-hydroxymethyl-7-oxahexadecyl lithium sulfonate
 8-hydroxymethyl-7-oxahexadecyl ammonium sulfonate
 8-hydroxymethyl-14 methyl-12-ethyl-7-oxapentadecyl ammonium sulfonate
 triethanol amine salt of 8-hydroxymethyl-5,5-dimethyl-7-oxahexadecyl sulfonic acid
 9-hydroxymethyl-8-oxahexadecyl sodium sulfonate
 9-hydroxymethyl-5,5-dimethyl-8-oxahexadecyl sodium sulfonate
 9-hydroxymethyl-8-oxaoctadecyl potassium sulfonate
 9-hydroxymethyl-8-oxadocosyl potassium sulfonate
 9-hydroxymethyl-8-oxahexadecyl lithium sulfonate
 9-hydroxymethyl-8-oxahexadecyl ammonium sulfonate
 9-hydroxymethyl-14 methyl-12-ethyl-8-oxapentadecyl ammonium sulfonate
 triethanol amine salt of 9-hydroxymethyl-5,5-dimethyl-8-oxahexadecyl sulfonic acid
 10-hydroxymethyl-9-oxahexadecyl sodium sulfonate
 10-hydroxymethyl-9-oxaeicosyl sodium sulfonate
 10-hydroxymethyl-5,5-dimethyl-9-oxahexadecyl sodium sulfonate
 10-hydroxymethyl-9-oxaoctadecyl potassium sulfonate
 10-hydroxymethyl-9-oxadocosyl potassium sulfonate
 10-hydroxymethyl-9-oxahexadecyl lithium sulfonate
 10-hydroxymethyl-9-oxahexadecyl ammonium sulfonate
 10-hydroxymethyl-14 methyl-12-ethyl-9-oxapentadecyl ammonium sulfonate
 triisopropanol amine salt of 10-hydroxymethyl-7,7-dimethyl-9-oxahexadecyl sulfonic acid
 11-hydroxymethyl-10-oxahexadecyl sodium sulfonate
 11-hydroxymethyl-10-oxaeicosyl sodium sulfonate
 11-hydroxymethyl-7,7-dimethyl-10-oxahexadecyl sodium sulfonate
 11-hydroxymethyl-10-oxaoctadecyl potassium sulfonate
 11-hydroxymethyl-10-oxadocosyl potassium sulfonate
 11-hydroxymethyl-10-oxahexadecyl lithium sulfonate
 11-hydroxymethyl-10-oxahexadecyl ammonium sulfonate
 11-hydroxymethyl-8-methyl-12-ethyl-10-oxapentadecyl ammonium sulfonate
 triethanol amine salt of 11-hydroxymethyl-7,7-dimethyl-10-oxahexadecyl sulfonic acid
 5-methyl, 5-(hydroxymethyl)-4-oxahexadecyl sodium sulfonate
 5-methyl, 5-(hydroxymethyl)-4-oxaeicosyl sodium sulfonate
 5-methyl, 5-(hydroxymethyl)-7,7-dimethyl-4-oxahexadecyl sodium sulfonate
 5-methyl, 5-(hydroxymethyl)-10-oxahexadecyl ammonium sulfonate
 5-methyl, 5-(hydroxymethyl)-8-methyl-12-ethyl-10-oxapentadecyl ammonium sulfonate
 triethanol amine salt of 5-methyl, 5-(hydroxymethyl)-7,7-dimethyl-10-oxahexadecyl sulfonic acid
 5-methyl, 5-(hydroxymethyl)-4-oxaoctadecyl potassium sulfonate
 5-methyl, 5-(hydroxymethyl)-4-oxadocosyl potassium sulfonate
 5-methyl, 5-(hydroxymethyl)-4-oxahexadecyl lithium sulfonate
 5-methyl, 5-(hydroxymethyl)-4-oxahexadecyl ammonium sulfonate

5-methyl, 5-(hydroxymethyl)-4-oxahexadecyl lithium sulfonate
 5-methyl, 5-(hydroxymethyl)-4-oxahexadecyl ammonium sulfonate
 5-methyl, 5-(hydroxymethyl)-8-methyl-12-ethyl-4-oxapentadecyl ammonium sulfonate 5
 triethanol amine salt of 5-methyl, 5-(hydroxymethyl)-7,7-dimethyl-4-oxahexadecyl sulfonic acid
 6-ethyl, 6-(hydroxymethyl)-5-oxahexadecyl sodium sulfonate 10
 6-ethyl, 6-(hydroxymethyl)-5-oxaeicosyl sodium sulfonate
 6-ethyl, 6-(hydroxymethyl)-7,7-dimethyl-5-oxahexadecyl sodium sulfonate
 6-ethyl, 6-(hydroxymethyl)-5-oxaoctadecyl potassium sulfonate 15
 6-ethyl, 6-(hydroxymethyl)-5-oxadocosyl potassium sulfonate
 6-ethyl, 6-(hydroxymethyl)-5-oxahexadecyl lithium sulfonate
 6-ethyl, 6-(hydroxymethyl)-5-oxahexadecyl ammonium sulfonate 20
 6-ethyl, 6-(hydroxymethyl)-8-methyl-12-ethyl-5-oxapentadecyl ammonium sulfonate
 triethanol amine salt of 6-ethyl, 6-(hydroxymethyl)-7,7-dimethyl-5-oxahexadecyl sulfonic acid 25
 8-isopropyl, 8-(hydroxymethyl)-7-oxahexadecyl sodium sulfonate
 8-isopropyl, 8-(hydroxymethyl)-7-oxaeicosyl sodium sulfonate
 8-isopropyl, 8-(hydroxymethyl)-5,5-dimethyl-7-oxahexadecyl sodium sulfonate 30
 8-isopropyl, 8-(hydroxymethyl)-7-oxaoctadecyl potassium sulfonate
 8-isopropyl, 8-(hydroxymethyl)-7-oxadocosyl potassium sulfonate 35
 8-isopropyl, 8-(hydroxymethyl)-7-oxahexadecyl lithium sulfonate
 8-isopropyl, 8-(hydroxymethyl)-7-oxahexadecyl ammonium sulfonate
 8-isopropyl, 8-(hydroxymethyl)-10-methyl-12-ethyl-7-oxapentadecyl ammonium sulfonate triethanol amine salt of 8-isopropyl, 8-(hydroxymethyl)-5,5-dimethyl-7-oxahexadecyl sulfonic acid 40
 10-t-butyl, 10-(hydroxymethyl)-9-oxahexadecyl sodium sulfonate 45
 10-t-butyl, 10-(hydroxymethyl)-9-oxaeicosyl sodium sulfonate
 10-t-butyl, 10-(hydroxymethyl)-7,7-dimethyl-9-oxahexadecyl sodium sulfonate 50
 10-t-butyl, 10-(hydroxymethyl)-9-oxaoctadecyl potassium sulfonate
 10-t-butyl, 10-(hydroxymethyl)-9-oxadocosyl potassium sulfonate
 10-t-butyl, 10-(hydroxymethyl)-9-oxahexadecyl lithium sulfonate 55
 10-t-butyl, 10-(hydroxymethyl)-9-oxahexadecyl ammonium sulfonate
 10-t-butyl, 10-(hydroxymethyl)-8-methyl-12-ethyl-9-oxapentadecyl ammonium sulfonate 60
 triethanol amine salt of 10-t-butyl, 10-(hydroxymethyl)-7,7-dimethyl-9-oxahexadecyl sulfonic acid
 5-(beta-hydroxyethyl)-4-oxahexadecyl sodium sulfonate
 5-(beta-hydroxyethyl)-4-oxaeicosyl sodium sulfonate
 5-(beta-hydroxyethyl)-7,7-dimethyl-4-oxahexadecyl sodium sulfonate 65
 5-(beta-hydroxyethyl)-4-oxaoctadecyl potassium sulfonate
 5-(beta-hydroxyethyl)-4-oxadocosyl potassium sulfonate
 5-(beta-hydroxyethyl)-4-oxahexadecyl lithium sulfonate
 5-(beta-hydroxyethyl)-4-oxahexadecyl ammonium sulfonate 70
 5-(beta-hydroxyethyl)-8-methyl-12-ethyl-4-oxapentadecyl ammonium sulfonate
 diethanol amine salt of 5-(beta-hydroxyethyl)-7,7-dimethyl-4-oxahexadecyl sulfonic acid 75

6-(gamma-hydroxypropyl)-5-oxahexadecyl sodium sulfonate
 6-(gamma-hydroxypropyl)-5-oxaeicosyl sodium sulfonate
 6-(gamma-hydroxypropyl)-7,7-dimethyl-5-oxahexadecyl sodium sulfonate
 6-(gamma-hydroxypropyl)-5-oxaoctadecyl potassium sulfonate
 6-(gamma-hydroxypropyl)-5-oxadocosyl potassium sulfonate
 6-(gamma-hydroxypropyl)-5-oxahexadecyl lithium sulfonate
 6-(gamma-hydroxypropyl)-5-oxahexadecyl ammonium sulfonate
 6-(gamma-hydroxypropyl)-8-methyl-12-ethyl-5-oxapentadecyl ammonium sulfonate
 triethanol amine salt of 6-(gamma-hydroxypropyl)-7,7-dimethyl-5-oxahexadecyl sulfonic acid
 7-(delta-hydroxybutyl)-6-oxahexadecyl sodium sulfonate
 7-(delta-hydroxybutyl)-6-oxaeicosyl sodium sulfonate
 7-(delta-hydroxybutyl)-6-oxahexadecyl sodium sulfonate
 7-(delta-hydroxybutyl)-8,8-dimethyl-6-oxahexadecyl sodium sulfonate
 7-(delta-hydroxybutyl)-6-oxaoctadecyl potassium sulfonate
 7-(delta-hydroxybutyl)-6-oxadocosyl potassium sulfonate
 7-(delta-hydroxybutyl)-6-oxahexadecyl lithium sulfonate
 7-(delta-hydroxybutyl)-6-oxahexadecyl ammonium sulfonate
 7-(delta-hydroxybutyl)-8-methyl-12-ethyl-6-oxapentadecyl ammonium sulfonate
 triethanol amine salt of 7-(delta-hydroxybutyl)-10,10-dimethyl-6-oxahexadecyl sulfonic acid
 5-hydroxyisopropylidene-4-oxahexadecyl sodium sulfonate
 5-hydroxyisopropylidene-4-oxaeicosyl sodium sulfonate
 5-hydroxyisopropylidene-7,7-dimethyl-4-oxahexadecyl sodium sulfonate
 5-hydroxyisopropylidene-4-oxaoctadecyl potassium sulfonate
 5-hydroxyisopropylidene-4-oxadocosyl potassium sulfonate
 5-hydroxyisopropylidene-4-oxahexadecyl lithium sulfonate
 5-hydroxyisopropylidene-4-oxahexadecyl ammonium sulfonate
 5-hydroxyisopropylidene-8-methyl-12-ethyl-4-oxapentadecyl ammonium sulfonate
 triethanol amine salt of 5-hydroxyisopropylidene-7,7-dimethyl-4-oxahexadecyl sulfonic acid
 7-hydroxyethylidene-6-oxahexadecyl sodium sulfonate
 7-hydroxyethylidene-6-oxaeicosyl sodium sulfonate
 7-hydroxyethylidene-8,8-dimethyl-6-oxahexadecyl sodium sulfonate
 7-hydroxyethylidene-6-oxaoctadecyl potassium sulfonate
 7-hydroxyethylidene-6-oxadocosyl potassium sulfonate
 7-hydroxyethylidene-6-oxahexadecyl lithium sulfonate
 7-hydroxyethylidene-6-oxahexadecyl ammonium sulfonate
 7-hydroxyethylidene-8-methyl-12-ethyl-6-oxapentadecyl ammonium sulfonate
 triethanol amine salt of 7-(delta-hydroxybutyl)-8,8-dimethyl-6-oxahexadecyl sulfonic acid
 5-methyl, 5-(beta-hydroxyethyl)-4-oxahexadecyl sodium sulfonate
 5-methyl-5-(beta-hydroxyethyl)-4-oxaeicosyl sodium sulfonate
 5-methyl-5-(beta-hydroxyethyl)-7,7-dimethyl-4-oxahexadecyl sodium sulfonate
 5-methyl-5-(beta-hydroxyethyl)-4-oxaoctadecyl potassium sulfonate
 5-methyl-5-(beta-hydroxyethyl)-4-oxadocosyl potassium sulfonate
 5-methyl-5-(beta-hydroxyethyl)-lithium sulfonate
 5-methyl-5-(beta-hydroxyethyl)-4-oxahexadecyl ammonium sulfonate
 5-methyl-5-(beta-hydroxyethyl)-8-methyl-12-ethyl-4-oxapentadecyl ammonium sulfonate
 triethanol amine salt of 5-methyl-5-(beta-hydroxyethyl)-7,7-dimethyl-4-oxahexadecyl sulfonic acid
 6-isopropyl-5-hydroxyisopropylidene-4-oxahexadecyl sodium sulfonate

6-isopropyl-5-hydroxyisopropylidene-4-oxaeicosyl sodium sulfonate
 6-isopropyl-6-hydroxyisopropylidene-7,7-dimethyl-5-oxahexadecyl sodium sulfonate
 6-isopropyl-6-hydroxyisopropylidene-5-oxaoctadecyl potassium sulfonate 5
 6-isopropyl-6-hydroxyisopropylidene-5-oxadocosyl potassium sulfonate
 6-isopropyl-6-hydroxyisopropylidene-5-oxahexadecyl lithium sulfonate 10
 6-isopropyl-6-hydroxyisopropylidene-5-oxahexadecyl ammonium sulfonate
 6-isopropyl-6-hydroxyisopropylidene-8 methyl-12-ethyl-5-oxapentadecyl ammonium sulfonate triethanol amine salt of 6-isopropyl, 6 hydroxyisopropylidene-7,7-dimethyl-5-oxahexadecyl sulfonic acid 15
 6-hydroxy-5-methyl-4-oxahexadecyl sodium sulfonate
 6-hydroxy-5-methyl-4-oxaeicosyl sodium sulfonate
 6-hydroxy-5-methyl-7,7-dimethyl-4-oxahexadecyl sodium sulfonate 20
 6-hydroxy-5-methyl-4-oxaoctadecyl potassium sulfonate
 6-hydroxy-5-methyl-4-oxadocosyl potassium sulfonate
 6-hydroxy-5-methyl-4-oxahexadecyl lithium sulfonate
 6-hydroxy-5-methyl-4-oxahexadecyl ammonium sulfonate 25
 6-hydroxy-5-methyl-8-methyl-12-ethyl-4-oxapentadecyl ammonium sulfonate
 triethanol amine salt of 6-hydroxy-5-methyl-12-ethyl-4-oxapentadecyl ammonium sulfonate
 6-hydroxy-5-ethyl-4-oxahexadecyl sodium sulfonate 30
 6-hydroxy-5-ethyl-4-oxaeicosyl sodium sulfonate
 6-hydroxy-5-ethyl-7,7-dimethyl-4-oxahexadecyl sodium sulfonate
 6-hydroxy-5-ethyl-4-oxaoctadecyl potassium sulfonate
 6-hydroxy-5-ethyl-4-oxadocosyl potassium sulfonate 35
 6-hydroxy-5-ethyl-4-oxahexadecyl lithium sulfonate
 6-hydroxy-5-ethyl-4-oxahexadecyl ammonium sulfonate
 6-hydroxy-5-ethyl-8-methyl-12-ethyl-4-oxapentadecyl ammonium sulfonate
 triethanol amine salt of 6-hydroxy-5-ethyl-12-ethyl-4-oxapentadecyl ammonium sulfonate 40
 7-hydroxy-6-isopropyl-5-oxahexadecyl sodium sulfonate
 7-hydroxy-6-isopropyl-5-oxaeicosyl sodium sulfonate
 7-hydroxy-6-isopropyl-9,9-dimethyl-5-oxahexadecyl sodium sulfonate 45

 6-hydroxy-5-methyl-4-thiahexadecyl sodium sulfonate
 6-hydroxy-5-methyl-7,7-diemthyl-4-thiahexadecyl sodium sulfonate
 6-hydroxy-5-methyl-4-thiadocosyl potassium sulfonate
 6-hydroxy-5-methyl-8 methyl-12-ethyl-4-thiapentadecyl ammonium sulfonate
 6-hydroxy-5-ethyl-4-thiahexadecyl sodium sulfonate
 6-hydroxy-5-ethyl-7,7-dimethyl-4-thiahexadecyl sodium sulfonate
 6-hydroxy-5-methyl-4-thiahexadecyl ammonium sulfonate
 7-hydroxy-6-isopropyl-5-thiahexadecyl sodium sulfonate
 7-hydroxy-6-isopropyl-5-thiadocosyl potassium sulfonate
 7-hydroxy-6-isopropyl-5-thiahexadecyl ammonium sulfonate
 8-hydroxy-7-isopropyl,11-methyl-6-thiaeicosyl sodium sulfonate
 8-hydroxy-7-isopropyl-11-methyl-6-thiaoctadecyl potassium sulfonate
 8-hydroxy-7-isopropyl-11-methyl-6-thiahexadecyl ammonium sulfonate
 10-hydroxy-9-butyl-8-thiaoctadecyl potassium sulfonate
 triethanol amine salt of 10-hydroxy-9-t-butyl-7,7-diemthyl-8-thiahexadecyl sulfonic acid
 Examples, by way of illustration only, of unsaturated alcohols include:
 allyl alcohol
 isopropenyl alcohol
 1-butene-3-ol
 3-buten-1-ol
 crotyl alcohol
 methallyl alcohol
 9-decene-1-ol
 3,5-dimethyl-5-hexene-3-ol
 2,3-dimethyl-4-pentene-2-ol
 3-ethyl-5-hexene-3-ol
 1-heptene-3-ol
 2-heptene-4-ol
 3-heptene-1-ol
 4-hexene-3-ol
 5-hexene-3-ol
 3-methyl-3-butene-2-ol
 2-methyl-1-heptene-3-ol
 3-methyl-5-hexene-3-ol
 2-methyl-1-pentene-3-ol
 2-methyl-4-pentene-3-ol
 4-methyl-1-pentene-3-ol
 4-methyl-3-pentene-2-ol
 10-undecene-1-ol
 In addition, examples of corresponding thiol derivatives, e.g. mercaptans, include:
 allyl mercaptan
 isopropenyl mercaptan
 1-butene-3-thiol
 3-butene-1-thiol
 3,5-dimethyl-5-hexene-3-thiol
 2,3-dimethyl-4-pentene-2-thiol
 3-ethyl-5-hexene-3-thiol
 9-decene-1-thiol

- 3,5-dimethyl-5-hexene-3-thiol
 2,3-diemthyl-4-pentene-2-thiol
 3-ethyl-5-hexene-3-thiol
 1-heptene-3-thiol
 2-heptene-4-thiol
 3-heptene-1-thiol
 4-hexene-3-thiol
 5-hexene-3-thiol
 3-methyl-3-butene-2-thiol
 2-methyl-1-heptene-3-thiol
 3-methyl-5-hexene-3-thiol
 2-methyl-1-pentene-3-thiol
 2-methyl-4-pentene-3-thiol
 4-methyl-1-pentene-3-thiol
 4-methyl-3-pentene-2-thiol
 10-undecene-1-thiol

The hydroxy ether or thioether sulfonates of the present invention are prepared, using one technique, by the reaction of long-chain epoxide with an unsaturated alcohol or thioalcohol (i.e. mercaptan) with subsequent sulfonation of the intermediate product in accordance with the following equations, illustrating the use of an alcohol:

wherein R_1 is as defined above; and R_9 is C_1 to C_{10} which together with $-\text{CH}=\text{CH}_2$ forms an unsaturated group within the scope of R_9 .

Reaction I above is preferably catalyzed by the employment of sodium, preferably dissolved in the alcohol reactant. Thus, while it has been established that almost quantitative yields of the unsaturated intermediate product can be produced by the use of sodium as the catalyst in the process of the present invention, it is, of course, obvious that any catalyst material capable of effecting the condensation of the alcohol and long-chain epoxide with the opening of the epoxy ring can be successfully employed in the process of the present invention. Such exemplary catalysts include for example BF_3 , BF_3 -dialkyl etherate, etc.

The reaction of the long-chain epoxide and alcohol is not critically dependent upon the choice of temperature, pressure or amount of reactants. Thus, while the epoxide and alcohol react in substantially stoichiometric proportions, it is possible to employ a relatively large excess of either the long-chain epoxide or the alcohol reactant without adversely effecting the reaction system. In this respect, it has been shown that the employment of such a relatively large excess of either reactant merely necessitates removal of the excess reactant from the reaction system and does not adversely effect the product or yield thereof.

Similarly, it has been found that the reaction of the present invention can be suitably run at ambient pressure or under increased pressure conditions, the pressure of the system having relatively little effect upon the yield and purity of the intermediate product and final product produced. For economic purposes however, it has been found most suitable to run the reaction under atmospheric pressure conditions.

Similarly, it has been determined that the temperature at which the reaction is run is not critical with respect to the purity and yield of both the intermediate product and the final product in accordance with the process of the present invention. Thus, temperatures ranging from ambient temperatures up through approximately 150°C . have been found suitable in accordance with the process of the present invention, although any temperature may be used provided the reactants are stable therat. The selection of any particular temperature will be dependent, inter alia, upon the specific reactants and the selection of catalyst, if any, employed. Suitable catalysts

include any basic or acidic material. Illustrative catalysts are alkali metals, alkalihydroxides, Lewis acids such as boron trifluoride, aluminum chloride, etc. The catalyst concentration is not critical, and as little as 0.001 percent may be used; the upper limit may be 10 percent.

It is pointed out that while the above description has been directed primarily to the employment of a single long-chain epoxide in the reaction with alcohol to produce a single unsaturated hydroxy ether intermediate product, it is of course obvious that mixtures of such long-chain epoxides can be suitably employed to produce a mixture of such unsaturated hydroxy ethers. The sulfonation of such mixture of products will produce a mixture of hydroxy ether sulfonates which mixture is exceptionally useful because of its detergency and fabric-softening ability. Accordingly, a suitable reaction mixture of long-chain epoxides has been found to be a mixture of C_{15} - C_{18} 1,2-epoxy alkanes.

It is within the contemplation of the present invention to carry out the processes for producing the compounds of this invention, including the 12-epoxyalkane-alcohol condensation reaction in the presence of inert diluent or mutual non-reactive solvents such as xylene, toluene, etc., and in the sulfonation phase of the process there may also be used aqueous alcohols e.g., aqueous methanol, ethanol, n-propanol, isopropanol, butanol, pyridine, etc.

The novel unsaturated hydroxy ether intermediate prepared by the reaction of the long-chain epoxide and unsaturated alcohol can be sulfonated to produce the novel detergent and fabric-softening compounds of the present invention in any suitable conventional manner. Thus, it has been found convenient to sulfonate the double bond of the novel intermediate compound with a bisulfite e.g., sodium bisulfite in the presence of an initiator. Suitable initiators include peroxide

initiators include for example tertiary butyl perbenzoates, di-*t*-butyl peroxide, dibenzoyl peroxide, dilauryl peroxide, etc.¹¹ Another initiator system is the nitrate/oxygen system e.g. potassium nitrate, lithium nitrate ammonium nitrate, alkaline earth nitrates and others, which do not accelerate bisulfite oxidation to sulfate in the presence of oxygen, preferably at a partial pressure of from 1 to 1.5 p.s.i.) Such a process which is conveniently employed in the sulfonation of double bonds is set forth in U.S. Pat. No. 2,504,411, the subject matter of which is incorporated herein by reference. While the temperature of the sulfonation reaction is not critical, generally slightly elevated temperatures are employed. Thus, for example, a temperature of from about 40° to 150°C . can be conveniently employed in the sulfonation of the novel unsaturated hydroxy ether compounds of the present invention.

Other synthetic routes may be used. For example, in place of the unsaturated alcohol, one may condense the epoxy alkane with an α , ω -halohydroxy compound, dehydrohalogenate and then sulfonate with bisulfite, or alternatively employ sodium sulfite (in lieu of dehydrohalogenation and bisulfite), i.e., Strecker reaction. Further vicinal glycols reacted with sultones yield the instant compounds.

The novel hydroxy ether sulfonates of the present invention, in addition to possessing excellent detergency and fabric-softening properties, have been found to be compatible with the various detergent builders and other additives conventionally employed in detergent compositions. Accordingly, it is possible to formulate a detergent composition based upon the hydroxy ether sulfonate as the detergent and fabric softener. Because of the unusual compatibility of the hydroxy ether sulfonates of the present invention with the various detergent builders, it is possible to prepare both solid-phase detergent compositions and single-phase liquid detergent compositions which could not be suitably prepared with the employment of conventional linear alkyl benzene sulfonates.

The new compounds of this invention and the new mixtures containing such compounds may be employed in a wide variety of detergent compositions, including light-duty liquid detergent formulations and granular compositions such as spray-dried built detergent powders. They may be used in

toilet bars for washing the hands, face and body (here, as in other formulations, their unexpected germicidal properties are highly advantageous) or in laundry detergent bars, containing appreciable amounts of builder salts, for washing clothes. They may also be used in hair-shampooing, hair-dyeing or other hair-treating or hair-conditioning compositions. They may also be used in dental creams or other dentifrices and in skin care preparations such as creams and lotions.

The novel detergent compounds of this invention may be used as such or as mixtures with other surface-active detergents. The added surface-active detergents may be of the anionic, nonionic, cationic or amphoteric types, or mixtures thereof.

The anionic surface active agents include those surface active or detergent compounds which contain an organic hydrophobic group and an anionic solubilizing group. Typical examples of anionic solubilizing groups are sulfonate, sulfate, carboxylate, phosphonate and phosphate. Examples of suitable anionic detergents which fall within the scope of the invention include the soaps, such as the water-soluble salts of higher fatty acids or rosin acids, such as may be derived from fats, oils and waxes of animal, vegetable or marine origin, e.g. the sodium soaps of tallow, grease, coconut oil, tall oil and mixtures thereof; and the sulfated and sulfonated synthetic detergents, particularly those having about eight to 26, and preferably about 12 to 22, carbon atoms to the molecule.

As examples of suitable synthetic anionic detergents there may be cited the higher alkyl mononuclear aromatic sulfonates such as the higher alkyl benzene sulfonates containing from 10 to 16 carbon atoms in the alkyl group in a straight or branched chain, e.g., the sodium salts of higher alkyl benzene sulfonates or of the higher alkyl toluene, xylene and phenol sulfonates; alkyl naphthalene sulfonate, ammonium diamyl naphthalene sulfonate, and sodium dinonyl naphthalene sulfonate. In one preferred type of composition there is used a linear alkyl 1 sulfonate having a high content of 3-(or higher) phenyl isomers and a correspondingly low content (well below 50 percent of 2-(or lower) phenyl isomers; in other terminology, the benzene ring is preferably attached in large part at the 3 or higher (e.g. 4, 5, 6 or 7) position of the alkyl group and the content of isomers in which the benzene ring is attached at the 2 or 1 position is correspondingly low. Particularly preferred materials are set forth in U.S. Pat. No. 3,320,174, May 16, 1967, of J. Rubinfeld.

The mixtures containing linear alkylbenzene sulfonates and the detergent compounds of this invention have unexpectedly good properties, particularly with respect to softening power. These mixtures are the invention of Harold Wixon.

Other anionic detergents are the olefin sulfonates, including long-chain alkene sulfonates, long-chain hydroxyalkane sulfonates or mixtures of alkenesulfonates and hydroxyalkanesulfonates. These olefin sulfonate detergents may be prepared, in known manner, by the reaction of SO_3 with long chain olefins (of 8 to 25, preferably 12-21 carbon atoms) of the formula $\text{R}'\text{CH-CHR}''$, where R' is alkyl and R'' is alkyl or hydrogen, to produce a mixture of sulfones and alkenesulfonic acids, which mixture is then treated to convert the sulfones to sulfonates. Examples of other sulfate or sulfonate detergents are paraffin sulfonates, such as the reaction products of alpha olefins and bisulfates (e.g. sodium bisulfate), e.g., primary paraffin sulfonates of about 10-20, preferably about 15-20 carbon atoms; sulfates or higher alcohols; salts of α -sulfofatty esters (e.g. of about 10-20 carbon atoms, such as methyl α -sulfomyristate or α -sulfotallowate).

Examples of sulfates of higher alcohols are sodium lauryl sulfate, sodium tallow alcohol sulfate, Turkey Red Oil or other sulfated oils, or sulfates of mono- or diglycerides of fatty acids (e.g. stearic monoglyceride monosulfate), alkyl poly (ethenoxyl) ether sulfates such as the sulfates of the condensation products of ethylene oxide and lauryl alcohol (usually having one to five ethenoxy groups per molecule); lauryl or other higher alkyl glyceryl ether sulfonates; aromatic poly (ethenoxyl) ether sulfates such as the sulfates of the condensation

products of ethylene oxide and nonyl phenol (usually having one to six oxyethylene groups per molecule).

The suitable anionic detergents include also the acyl sarocosinates (e.g. sodium lauroylsarcosinate) the acyl esters (e.g. oleic acid ester) of isethionates, and the acyl N-methyl taurides (e.g. potassium N-methyl lauroyl- or oleyl tauride).

The most highly preferred water-soluble anionic detergent compounds are the ammonium and substituted ammonium (such as mono-, di- and triethanolamine), alkali metal (such as sodium and potassium) and alkaline earth metal (such as calcium and magnesium) salts or the higher alkyl benzene sulfonates, olefin sulfonates, the higher alkyl sulfates, and the higher fatty acid monoglyceride sulfates. The particular salt will be suitably selected depending upon the particular formulation and the proportions therein. Nonionic surface-active

agents include those surface-active or detergent compounds which contain an organic hydrophobic group and a hydrophilic group which is a reaction product of a solubilizing group such as carboxylate, hydroxyl, amide or amino with ethylene oxide or with the polyhydration product thereof, polyethylene glycol.

As examples of nonionic surface-active agents which may be used there may be noted the condensation products of alkyl phenols with ethylene oxide, e.g., the reaction product of isooctyl phenol with about six to 30 ethylene oxide units; condensation products of alkyl thiophenols with 10 to 15 ethylene oxide units; condensation products of higher fatty alcohols such as tridecyl alcohol with ethylene oxide; ethylene oxide addends of monoesters of hexahydric alcohols and inner ethers thereof such as sorbitan monolaurate, sorbitol monoleate and mannitol monopalmitate, and the condensation products of polypropylene glycol with ethylene oxide.

Cationic surface-active agents may also be employed. Such agents are those surface-active detergent compounds which contain an organic hydrophobic group and a cationic solubilizing group. Typical cationic solubilizing groups are amine and quaternary groups.

As examples of suitable synthetic cationic detergents there may be noted the diamines such as those of the type $\text{RNHC}_2\text{H}_4\text{NH}_2$ wherein R is an alkyl group of about 12 to 22 carbon atoms, such as N-2-aminoethyl stearyl amine and N-2-aminoethyl myristyl amine; amide-linked amines such as those of the type $\text{R}'\text{CONHC}_2\text{H}_4\text{NH}_2$ where R' is an alkyl group of about nine to 20 carbon atoms, such as N-2-amino ethylstearyl amide and N-amino ethyl myristyl amide; quaternary ammonium compounds wherein typically one of the groups linked to the nitrogen atom is an alkyl group of about 12 to 18 carbon atoms and three of the groups linked to the nitrogen atom are

alkyl groups which contain one to three carbon atoms, including such one to three carbon alkyl groups bearing inert substituents, such as phenyl groups, and there is present an anion such as halogen, acetate, methosulfate, etc. Typical quaternary ammonium detergents are ethyl-dimethyl-stearyl ammonium chloride, benzyl-dimethyl-stearyl ammonium chloride, benzyl-dimethyl-stearyl ammonium chloride, trimethyl stearyl ammonium chloride, trimethyl-cetyl ammonium bromide, dimethyl-ethyl diaryl ammonium chloride, dimethyl-propyl-myristyl ammonium chloride, and the corresponding methosulfates and acetates.

Examples of suitable amphoteric detergents are those containing both an anionic and a cationic group and a hydrophobic organic group, which is advantageously a higher aliphatic radical, e.g. of 10-20 carbon atoms. Among these are the N-long-chain alkyl aminocarboxylic acids (e.g. of the formula

70 the N-long-chain alkyl iminodcarboxylic acids (e.g. of the formula $\text{RN}(\text{R}'\text{COOM})_2$) and the N-long-chain alkyl betaines (e.g. of the formula

where R is a long-chain alkyl group, e.g. of about 10-20 carbons, R' is a divalent radical joining the amino and carboxyl portions of an amino acid (e.g. an alkylene radical of one to four carbon atoms), M is hydrogen or a salt-forming metal, R² is a hydrogen or another monovalent substituent (e.g. methyl or other lower alkyl), and R³ and R⁴ are monovalent substituents joined to the nitrogen by carbon-to-nitrogen bonds (e.g. methyl or other lower alkyl substituents). Examples of specific amphoteric detergents are N-alkyl-beta-aminopropionic acid; N-alkyl-beta-iminodipropionic acid, and N-alkyl, N,N-dimethyl glycine; the alkyl group may be, for example, that derived from coco fatty alcohol, lauryl alcohol, myristyl alcohol (or a lauryl-myristyl mixture), hydrogenated tallow alcohol, cetyl, stearyl, or blends of such alcohols. The substituted aminopropionic and iminodipropionic acids are often supplied in the sodium or other salt forms, which may likewise be used in the practice of this invention. Examples of other amphoteric detergents are the fatty imidazolines such as those made by reacting a long chain fatty acid (e.g. of 10 to 20 carbon atoms) with diethylene triamine and monohalocarboxylic acids having two to six carbon atoms, e.g. 1-coco-5-hydroxethyl-5-carboxymethylimidazoline; betaines containing a sulfonic group instead of the carboxylic group; betaines in which the long-chain substituent is joined to the carboxylic group without an intervening nitrogen atom, e.g. inner salts of 2-trimethylamino fatty acids such as 2-trimethylaminolauric acid, and compounds of any of the previously mentioned types but in which the nitrogen atom is replaced by phosphorus.

Water-soluble builder salts may also be present, in the usual proportions, in the detergent formulations when heavy-duty cleaning is desired. These salts include phosphates and particularly condensed phosphates (e.g. pyrophosphates or tripolyphosphates), as well as organic builders such as salts of nitrilotriacetic acid or ethylene diamine tetracetic acid. Sodium and potassium salts are preferred. Specific examples are sodium tripolyphosphate, potassium pyrophosphate, sodium hexametaphosphate, sodium tetraborate, sodium silicate, salts (e.g. Na salt) of methylene diphosphonic acid, trisodium nitrilotriacetate, or mixtures of such builders, including mixtures of pentasodium tripolyphosphate and trisodium nitrilotriacetate in a ratio, of these two builders, of 1:10 to 10:1, e.g. 1:1. The proportions of builder salt may be, for example, 50 parts or more (e.g. 50 to 1,000 parts) per 100 parts of detergent.

The detergent formulation may also contain other ingredients. Among these are soil-suspending agents such as sodium carboxymethyl cellulose or polyvinyl alcohol, preferably both, or other soluble polymeric materials, such as methyl cellulose (the amount of suspending agent being, for example, in the range of about 1/20 percent to 2 percent); antioxidants such as 2,6-di-tert-butylphenol, or other phenolic antioxidant materials (e.g. in amounts in the range of about 0.001 to 0.1 percent); coloring agents and optical brightening agents or fluorescent dyes in amounts in the range of, for example, about 1.20 percent to 1/2 percent. Among the optical brightening agents are such compounds as the fluorescent dyes of the stilbene type, e.g. sodium 2-sulfo-4-(2-naphtho-1,2-triazole) stilbene; disodium 4,4'-bis(4-anilino-6-morpholine-s-triazin-2-yl-amino) stilbenedisulfonate; or disodium 4,4'-bis(4,6-dianilino-s-triazin-2-yl-amino)-2,2'-stilbenedisulfonate; or of the oxazole type, e.g. having a 1-phenyl 2-benzoxazole ethylene structure. In preparing aqueous liquid formulations in particular, hydrotropic materials such as lower alkyl aryl sulfonates, e.g. sodium tolueno- or xylene-sulfonate, may be used where desired or necessary; in general, these materials are present in minor amounts, usually in the range of about 1/2 to 15 percent (e.g. 10 percent) of the total liquid composition.

One may also add known germicidal ingredients to the detergent compositions. These include halogenated carbanilides, e.g. trichlorocarbanilide, halogenated salicylanilide, e.g. tribromosalicylanilide, bisphenols, e.g. hexachlorophene, halogenated trifluoromethylidiphenyl urea, zinc salt of 1-hydroxy-2-pyridinethione and the like (e.g. in amounts in the

range of about 1/50 percent to 2 percent).

Opacifiers, perfumes, and antitarnishing agents may also be included in the detergent compositions containing the novel products of this invention, as may oxygen- and chlorine-releasing bleaches, such as sodium perborate or sodium or potassium dichloroisocyanurate. Heavy-duty detergent compositions containing the new products may also contain sodium bromide (e.g. in amount of 0.1 to 1 percent) to improve the bleaching effect of sodium hypochlorite present in the wash water.

The detergent compositions containing the novel products of this invention may also contain enzymes to assist in the removal of stains. Particularly important among these are the proteolytic enzymes which such materials as pepsin, trypsin, chymotrypsin, papain, bromelin, colleginase, keratinase, carboxylase, amino peptidase, elastase, substilisina and aspergilopepidase A and B. Among commercially available enzymes are Alcalcase and Maxatase. The enzyme is preferably present in powdered form and is admixed into the detergent formulation, typically in amount of about 0.001 percent to 4 percent of the total formulation, preferably about 0.05-1 percent. The combination of the novel products of this invention with enzymes yields particularly efficacious results. The enzyme-containing product can be used in cool or tepid water or in hot water.

The manufacture of detergent products in bar form, e.g. toilet bars and laundry bars, from olefin sulfonate detergents is described in Belgian Pat. No. 698,280. The novel hydroxy ether sulfonate compounds of this invention may each be substituted for the olefin sulfonates in the same proportions in each of the general and specific formulations set forth in that patent. The same or similar processing techniques may be used for blending the ingredients and for making the bars.

In the manufacture of oral preparations, the novel materials of this invention may be incorporated in toothpastes, dental creams, tooth powders, liquid dentifrices, mouth washes or rinses, dental chewing gums, lozenges or troches. Thus, in a tooth paste the composition may comprise some 20-75 percent of dental polishing agent, together with water, a humectant such as glycerol, and a gelling agent such as sodium carboxymethyl cellulose. Fluorides such as stannous fluoride may be present. In general, the novel hydroxy ether sulfonate compounds of this invention may each be substituted for the olefin sulfonates in each of the general and specific formulations set forth in the applications of Bouchal and Salzmann, Ser. No. 579,497 and of Rubinfeld and Levinsky, Ser. No. 579,524 now abandoned, each filed Sept. 15, 1966.

Shampoo formulations may comprise simple dispersions of the new detergent materials of this invention in water, e.g. in the form of alkanolammonium salts thereof, or combinations containing minor proportions of foam-boosting agents such as fatty acid (e.g. lauric/myristic) mono- or di-ethanolamides or the corresponding isopropanolamides, or amine oxides such as lauryl dimethylamine oxide. Other surface active detergents such as soaps and sodium lauryl sulfate may also be present.

EXAMPLE I

Preparation of:

0.3 grams of sodium is dissolved in 100 ml. of allyl alcohol and 48 grams (0.2 moles) of 1,2-hexadecane epoxide is added and the mixture refluxed for 4.5 hours. When the reaction begins, the temperature of the refluxing system is 966° C., the temperature rising slowly during the course of the reaction. After the reaction mixture has refluxed for 2.5 hours the temperature has risen to 100.6° C.; no further rise in temperature

is observed. The course of the reaction is followed by means of gas phase chromatography. The column used is a 2-foot "Silicon-rubber" column (2 percent SE-30 on Chromosorb W). The temperature is 100°C. when the sample is injected, followed by a programmed temperature rise of 15°C. per minutes. The original epoxide appears as a peak after 6.6 minutes in the column. After 3.5 hours of reflux the epoxide peak has almost disappeared, while the formation of the product can be seen as a strong peak that appears after 9 minutes in the column. After 4.5 hours of reflux the epoxide peak has disappeared completely.

After neutralization with concentrated hydrochloric acid the excess alcohol is evaporated and the residue is distilled under vacuum. This yields 43.5 g. (73 percent yield) of a colorless liquid, boiling range 155°-156°C./0.8 mm. Hg, freezing point 32.5°C.

Elemental analysis of the compound corresponds to the formula: $C_{18}H_{38}O_2$.

The infrared spectrum has the following characteristic absorptions:

2.9 microns	Strong band due to O-H of an alcohol
6.04 microns	Weak band due to a carbon-carbon double bond.
10.05 microns	Two strong bands due to a terminal vinyl group.
10.75 microns	Strong, broad band due to secondary hydroxyl and ether groups.
8.9-9.2 microns	

No band is observed in the 9.6 micron region where primary hydroxyl groups normally absorb. The infrared spectrum thus corresponds to the following structure:

The unsaturated hydroxyether produced above is sulfonated by dissolving 15 grams of the unsaturated intermediate compound (0.05 moles) in 25 milliliters of methanol, adding 5.2 grams of sodium bisulfite dissolved in 10 milliliters water, and adding 0.5 milliliters of tertiary butyl perbenzoate as a catalyst. This mixture is stirred at 75°C., and the reaction is followed by gas phase chromatography as above, this time by watching the disappearance of the peak at 9 minutes which is due to the unsaturated hydroxyether. After 3 hours at 75°C., most of the unsaturated hydroxyether has reacted. After 5 hours of reaction, the mixture is cooled to room temperature and then stirred into 300 milliliters of acetone. The white solid which precipitates is filtered off and recrystallized from a water/methanol mixture. After drying, 16.0 g. of a white solid is obtained (80 percent yield). A melting point could not be obtained since decomposition occurs around 175°C.

The infrared spectrum and elemental analysis correspond to the following structure:

EXAMPLE II

The general procedure of example I is repeated using 0.23 g. of sodium in 100 ml. of allyl alcohol and adding thereto, 54 g. (0.2 moles) of 1,2-octadecane epoxide. Vacuum fractionation of the residue, after removal of the excess allyl alcohol yields 50 g. of a white product; melting point 43°-44°C.; boiling point 175°-180°C./0.8 mm. of mercury. Infrared spectrum analysis and elemental analysis correspond to the product of the formula:

Sulfonation and isolation is carried out as in example I using 11.5 g. of sodium bisulfite dissolved in 22 ml. of water and adding the solution to a solution of 30 g. of the above unsaturated hydroxyether in 50 ml. of methanol. One ml. of tertiary butyl perbenzoate is added as a catalyst. The isolated product, by infrared spectrum and elemental analysis, has the structure:

This product decomposes at about 175°C.

EXAMPLE III

Example I is again repeated using an equivalent amount of 1,2-dodecane epoxide. The resultant unsaturated ether product has a boiling point of 117°C./0.5 mm. Hg and has the formula:

Sulfonation as in example I yields a product of the formula:

EXAMPLE IV

The reaction of hexadecane-1,2-epoxide with allyl alcohol, using boron trifluoride etherate as catalyst

To 116 grams allyl alcohol containing 0.5 milliliters boron trifluoride diethyl etherate is added 240 grams (1 mole) of the epoxide dropwise from an addition funnel while stirring rapidly. The addition of the epoxide is complete in 20 minutes; during the reaction the temperature rises from 25° to 80°C. As gas chromatogram performed as described under example I shows that all the epoxide has reacted. After the excess allyl alcohol has been removed by distilling at reduced pressure, a sample of the reaction product is chromatographed on a 6 feet DEGS column (20 percent Diethylene Glycol Succinate on Chromosorb W); temperature 220°C., isothermal.

Two peaks are observed, at 10.6 minutes and at 12.5 minutes. This shows that the reaction had yielded two products, via the reaction:

NMR and infrared techniques prove the presence of primary and secondary alcohol groups. The areas under the two peaks correspond to 73.5 percent of the secondary alcohol (1) and 26.5 percent of the isomeric primary alcohol (2).

Sulfonation of the mixture:

Ninety grams (0.3 mole) of the reaction product above are dissolved in 100 milliliters methanol; a solution of 31.2 grams (0.3 mole) sodium bisulfite in 60 milliliters water is added and finally 2.5 milliliters tertiary butyl perbenzoate. The reaction flask is equipped with magnetic stirring, sealed and stirred at 130° C. for 1 hour. After cooling to room temperature the mixture is stirred into 300 milliliters of acetone. The sodium sulfonate that precipitates is filtered off and dried. Yield is 85 grams (70 percent). The product has the following composition:

EXAMPLE V

Example IV is repeated except that the two isomeric alcohols are separated by the chromatographic procedure described in example IV and the pure primary unsaturated alcohol product is sulfonated as in example IV.

EXAMPLE VI

The general procedure of example IV is followed using 8.6 g. (0.1 mole) of 1-pentene-5-ol containing 2 drops of boron trifluoride etherate (diethyl), and adding dropwise while stirring, 18.4 g. (0.1 mole) of dodecane-1,2-epoxide. Two main products are formed (i.e. a primary and a secondary alcohol) as shown by the gas chromatogram. The products are isomeric and have the structures:

The relative amounts are determined by calculations based upon the areas under the peaks obtained in the chromatogram. The mixture has a boiling point range of 140°–146° C. at 0.4 mm. Hg. The infrared spectrum is shown in FIG. 1.

The mixture produced above is sulfonated using 10 g. of said mixture and a solution of 4.55 g. NaHSO₃ and 0.25 ml. of tertiary butyl perbenzoate in 10 ml. of methanol and 7.5 ml. of water. Stirring is carried out for 1½ hours at 135° C. After cooling, 200 ml. of acetone are stirred into the mixture. A white precipitate forms which is filtered and dried. The yield is 12 g. (85 percent).

The sulfonated mixture contains:

EXAMPLE VII

The previous example is repeated using 0.15 moles of the alcohol and 0.1 mole of hexadecane-1,2-epoxide. The isolated unsaturated alcohol mixture has a boiling point range of 178°–184° C. at 0.6 mm. Hg. The molecular weight is 326. The product is a liquid at room temperature and contains:

16.3 g. (0.05 moles) of the above mixture of unsaturated alcohols, 16 ml. methanol, 0.3 ml. t-butyl perbenzoate, 5.7 g. (0.055 moles) of sodium bisulfite dissolved in 11.5 ml. of water are stirred for 1 hour at 135° C. Then the mixture is poured into acetone and the resultant precipitate is filtered off and dried. Yield is 16.59 g. (77 percent). The product is a mixture of:

EXAMPLE VIII

The procedures of examples VI and VII are repeated insofar as the production of the unsaturated alcohols is concerned. In each case, the mixture is separated into the individual component isomers by a gas phase chromatographic column separation technique. The resultant four products (two isomers of example VI and two isomers of example VII) are sulfonated in examples VI and VII respectively using equivalent amounts of reactants.

EXAMPLE IX

The hydroxy ether sulfonates prepared in examples I to III are tested for their detergency relative to linear tridecyl benzene sulfonate, a commercially available detergent. The detergency of the materials produced in examples I to III relative to the control is investigated in both soft and hard water and both hot and cold water.

The results of the Spangler soil detergency tests are shown in table I below:

TABLE I

Spangler Soil* Detergency Test Results					
Temperature and Water Hardness	ΔRd** (Soil Removal)			Control LTBS)	
	Ex. 1	Ex. 2	Ex. 3		
70° F., N.B.*** Tap (90 p.p.m.)	+19.3	+19.6	+17.6		(linear tridecyl sulfonate)
70° F., (300 p.p.m.)	+16.0	+14.9	+11.2	+9.3	
120° F., N.B. Tap	+19.7	+20.8	+17.4	+19.9	
120° F., (300 p.p.m.)	+16.5	+15.9	+12.8	+11.6	

*The Spangler Soil test is carried out using cotton percale swatches (3 inches by 6 inches) soiled with synthetically prepared sebum soil employing 1.5 g. of test detergent and 1 liter of water; the wash cycle is 10 minutes at 100 c.p.m. agitation followed by 5 minutes rinse in same water used in wash. The test detergent is comprised of:

15 percent active sulfonate

60 35 percent sodium tripolyphosphate

50 percent sodium sulfate

**a value indicates soil removal.

***New Brunswick, New Jersey.

The results shown above indicate an unexpectedly excellent detergency in hard water and soft water, both cold and hot, as compared to the commercial detergent linear tridecyl benzene sulfonate. Accordingly, this exemplifies the unusually good detergency properties of the novel hydroxy ether sulfonates of the present invention.

EXAMPLE X

75 The hydroxy ether sulfonate produced in example I is tested

for fabric-softening ability in a towel test. The water employed in the foregoing softening test is 120° F., New Brunswick, N.J., tap water. A controlled detergent composition is prepared by combining 40 grams of sodium tripolyphosphate and 10 grams of active ingredient of linear dodecyl benzene sulfonate. Ten grams of the hydroxy ether sulfonate produced in example I is also added to 40 grams of the detergent builder sodium tripolyphosphate.

On a scale rating softness from 1 to 10, 10 being maximum softening of the fabric, the control containing the detergent builder and commercial detergent produces a result of 1, while the composition containing the hydroxy ether sulfonate in accordance with the present invention produces a result of 8.

This test, therefore indicates that the hydroxy ether sulfonates of the present invention, in addition to possessing excellent detergency, also possess excellent fabric-softening characteristics.

EXAMPLE XI

In accordance with the procedure of example III, the following hydroxy ether sulfonates are prepared:

In all cases, the hydroxy ether sulfonate is prepared by reacting the corresponding long-chain epoxide with allyl alcohol to form the unsaturated hydroxy ether intermediate with sulfonation of the unsaturated intermediate with sodium, potassium, or ammonium bisulfite to produce the desired hydroxy ether sulfonate.

EXAMPLE XII

The hydroxyether sulfonate products of examples IV, VI and VII are tested as in example IX with the following results:

TABLE II

Temperature and water hardness	Spangler Soil Detergency Test Results			55
	Ex. IV	Ex. VI	Ex. VII	
70° F. (N.B. Tap)	+18.5	+17.1	+20.4	+18.7
70° F. (300 p.p.m.)	+15.0	+12.0	+17.2	+8.9
120° F. (N.B. Tap)	+19.7	+18.7	+19.7	+19.5
120° F. (300 p.p.m.)	+18.1	+14.3	+19.6	+13.1

Again the outstanding overall performances in both hot and cold water at both hardnesses of these products is demonstrated.

EXAMPLE XIII

Example I is repeated using the following thioalcohols (in equivalent amounts) in place of allyl alcohol.

- A. allyl mercaptan
- B. 1butene-3-thiol
- C. 3,5-dimethyl-5-hexene-3-thiol
- D. 9-decene-1-thiol

The final products have the formulas:

EXAMPLE XIV

Example I is repeated except that in the sulfonation ammonium bisulfite is used in place of the sodium salt. The corresponding ammonium compound is produced.

EXAMPLE XV

Example I is repeated except that the final product is acidified in water, the aqueous solution extracted with alcohol and the acid form neutralized with triethanolamine. Isolation is done similarly as in example I by precipitation with acetone.

While various embodiments of the present invention have been described by reference to the foregoing examples it is to be understood that the present invention is in no way to be deemed as limited thereto but should be construed so as broadly as all or any equivalents thereof.

What is claimed is:

1. Novel compounds which in the free acid form have the formula:

wherein:

1. R_1 is a straight or branched higher alkyl group of C_6 to C_{30} ;
2. R_2 is a straight or branched alkylene of C_3 to C_{12} ;
3. R_3 to R_7 are, independently, hydrogen, straight or branched alkyl of C_1 to C_{16} ;
4. Z is oxygen or sulfur;
5. x and y have the values 0 or 1 and $x+y=1$; and
6. when x equals 0 the depicted OH group is attached directly to C^* .
2. Compounds of claim 1 wherein Z is oxygen.
3. Compounds of claim 1 wherein Z is sulfur.
4. Compounds of claim 2 wherein R_1 is C_{10} alkyl.
5. Compounds of claim 2 wherein R_1 is C_{14} alkyl.
6. Compounds of claim 2 wherein R_1 is C_{16} alkyl.
7. Compound of claim 4 wherein
  1. R_3 , R_4 and R_7 are hydrogen, and
  2. R_2 is C_3 alkylene.
8. Compound of claim 5 wherein
  1. R_5 , R_6 and R_7 are hydrogen, and
  2. R_2 is C_3 alkylene.
9. Compound of claim 5 wherein
  1. R_3 , R_4 and R_7 are hydrogen, and
  2. R_2 is C_5 alkylene.
10. Compound of claim 9 wherein
  1. R_3 , R_4 and R_7 are hydrogen, and
  2. R_2 is C_5 alkylene.
11. A process for producing the compounds of claim 1 which comprises reacting a 1,2-epoxy C_8 to C_{32} alkane with a C_2 to C_{10} olefinically unsaturated alcohol or thiol and thereafter sulfonating the resultant product with sodium bisulfite in the presence of a peroxide initiator.
12. A process as defined in claim 11 wherein from 0.001 percent to about 10 percent of a catalyst is employed in the epoxy-alcohol reaction step.
13. A process as defined in claim 12 wherein the said catalyst is sodium.
14. Compounds of claim 1 wherein x equals 1.
15. Compounds of claim 1 wherein y equals 1.
